WHEELED TOY AXLE MOUNTING

James H. Norton, Auburn, Ind., assignor to
 Auburn Rubber Corporation, Auburn, Ind., a
 corporation of Delaware

Application August 20, 1946, Serial No. 691,715

7 Claims. (Cl. 46—221)

1

This invention relates to wheeled toys of the type in which suitable supporting wheels are attached to a body which may be formed of any suitable material, such as, for example, a flexible and elastic composition suitable for molding.

The object of the invention is to provide a wheeled toy so constructed that it is inexpensive to manufacture but of strong and durable construction, capable of withstanding rough usage.

It is also an object to so mount the supporting wheels and axles that they are cushioned and reinforced by the body in such manner that they can withstand heavy thrusts without distortion.

With the above and other objects in view, the invention may be said to comprise the wheeled toy as illustrated in the accompanying drawings, hereinafter described and particularly set forth in the appended claims, together with such variations and modifications thereof as will be apparent to one skilled in the art to which the invention pertains.

Reference should be had to the accompanying drawings forming a part of this specification, in which:

Fig. 1 is a side elevation of the wheeled toy with its front portion broken away and shown in longitudinal vertical section;

Fig. 2 is a bottom plan view of the toy;

Fig. 3 is a fragmentary, vertical longitudinal section through the front end of the molded body;

Fig. 4 is a side elevation of the axle retaining clip, and

Fig. 5 is a section taken on the line indicated at 5—5 in Fig. 4.

The accompanying drawings show an embodiment of the invention in which the wheeled toy has a one-piece, hollow molded body 10 composed of flexible and elastic rubber-like material molded to a form simulating the body of an automobile. The body 10 is hollow and is provided with spaced side walls 11 which are shaped to correspond to the sides of an automobile body. In the embodiment shown, the side walls 11 have front and rear thickened portions 12 and 13 that simulate the fenders of an automobile and these thickened portions are provided with downwardly facing substantially semi-circular wheel recesses 14. At the inner sides of the wheel recesses and centrally thereof the side walls are provided at their lower edge with axle receiving notches 15. The body is also provided with integral transverse webs 16 extending between and which may connect the thickened portions 12 and 13 of the side walls directly above the axle receiving notches 15. Each of the transverse webs 16 lies in a plane containing the axes of one pair of

2

the axle receiving notches 15 and extends downwardly toward the notches 15, so that the bottom edge 17 thereof is in the region of the bottoms or upper portions of the notches 15 as viewed in Fig. 3. The bottom edge 17 of each transverse web 16 may be disposed above the notches 15 or may extend down to substantially the same plane as the bottoms or upper portions of the notches 15.

- 10 An axle 18 having wheels 19 mounted for rotation thereon is carried in the notches 15. When the bottom edge 17 of the web is in the plane of the bottoms of the notches 15 it will engage the axle 18 and thus prevent vertical movement 15 of the axle. In this instance the axle may be held against rotation by frictional engagement with the edge 17 of the web 16 leaving the wheels free to rotate about the axle. When the bottom edge 17 of the web 16 is slightly spaced upwardly 20 from the notches 15, the axle is also free to rotate and in this instance if desired the wheels may be fixed to the axle so that they rotate with the axle. If desired, the wheels may be held in place on the axle by suitable means such as by 25 expanding the ends of the axle after the wheels are assembled thereon. However, when the toy is provided with spaced side wall portions to provide a wheel recess 14 as shown in Fig. 2, it is not necessary to secure the wheels against disassembly from the axle since the wheels will be restrained from longitudinal movement along the axle sufficient for removal of the wheels by the side wall portions defining the recess 14.

The axle 18 may be secured to the body of the toy by suitable means which will embrace the axle and be in gripping engagement with the body. For example staples could be inserted which will straddle the axle and be embedded in the side wall portions of the body. A preferred method of securing the axle to the body is disclosed in the drawing. In this embodiment a separate gripping member, shown as U-shape in cross section, is employed. This gripping member or clip 21 is adapted to straddle the axle 18 with its arms and free ends embracing 40 and secured to the web 16. Figs 4 and 5 illustrate the clip 21 as being provided with a plurality of integrally projecting prongs 22 which will bite into the opposite faces of the web 16 to firmly hold the clip in place. If the toy is assembled in an upside down position the axle may be disposed on the toy so that the wheels are in the recesses 14 with the axle lying in the notches 16, then the clip 21 may be disposed over the axle with its arms and free ends overlapping the web 16. A suitable tool such as pliers or

the like may then be used to force the legs of the U-shaped clip into close frictional engagement with the web so that the prongs 22 will be embedded into the web to securely hold the axle to the body.

Since the body 10 is formed of flexible and elastic material, the axle 18 and wheels 19 are yieldably supported on the body and in order to strengthen the body the webs 16 are preferably tapered downwardly so as to provide a relatively stiff upper portion to receive the thrusts transmitted to the body through the supporting wheels 19.

Although the invention has been shown and described as applied to a toy automobile of flexible and elastic material, it may be seen that it may be applied with equal advantage to many other wheeled toys composed of various materials. Examples of suitable material are moldable plastics of both thermosetting and thermoplastic nature, natural and synthetic rubbers, particularly those vulcanizable with sulfur, reclaimed rubber or mixtures of the above. It is generally preferable to employ a material which is both flexible and elastic, since the resultant product is yieldable with no sharp edges and much safer for children to play with.

It is to be understood that variations and modifications of the specific devices herein shown and described for purposes of illustration, may be made without departing from the spirit of the invention.

What I claim is:

1. A wheeled toy comprising a hollow molded body having spaced side wall portions provided at their bottoms with transversely alined downwardly opening axle receiving notches on their bottom edges, said body having an integral cross web connecting said side wall portions of the body and lying in a plane containing the axes of said notches, an axle seated in said notches, wheels on said axle, and a U-shaped attaching member straddling said axle and web, engaging said axle and having its free end portions fastened to said web.

2. A toy vehicle comprising a hollow molded body of elastic and flexible rubber-like material and having spaced side walls with thickened portions adjacent the front and rear ends thereof provided with downwardly opening wheel recesses, said walls having axle receiving notches at the inner sides of said recesses, said body having transverse integral webs connecting the front thickened portions and connecting the rear thickened portions, each of said webs lying in a plane containing the axes of opposing axle receiving notches and having its bottom edge spaced above said notches, axles seated in said notches, wheels on said axles and projecting into said recesses, and a U-shaped clip straddling each axle and the web alined therewith, said clip engaging the axle to hold it in said notches, said clip having prongs on the inner sides of the arms thereof in gripping engagement with said web.

3. A wheeled toy comprising a hollow body portion having spaced side wall portions provided at their bottoms with transversely alined axle receiving notches, a transverse web portion integral with said body and lying in a plane containing the axes of opposing axle receiving notches, an axle mounted in said notches and carrying wheels, and means embracing said axle and secured to said transverse web to hold said axle in assembled position with said body during rotation of said wheels, said means comprising

4 a sheet metal substantially U-shaped clip with its free ends in secure gripping engagement with said transverse web.

5. A wheeled toy comprising a hollow body portion having spaced side wall portions provided at their bottoms with transversely alined axle receiving notches, a transverse web portion integral with said body and lying in a plane containing the axes of opposing axle receiving notches, an axle mounted in said notches and carrying wheels, and means embracing said axle and secured to said transverse web to hold said axle in assembled position with said body during rotation of said wheels, said means comprising a U-shaped member having projections on its free ends embedded in said transverse web in gripping engagement therewith.

5. A wheeled toy comprising a hollow body portion having spaced side wall portions provided at their bottoms with transversely alined axle receiving notches, a transverse web portion integral with said body and lying in a plane containing the axes of opposing axle receiving notches and extending downwardly to the upper portions of said notches, an axle mounted in said notches and carrying wheels, and means embracing said axle and secured to said transverse web to hold said axle in assembled position with said body during rotation of said wheels, said means comprising a sheet metal substantially U-shaped member extending over a major portion of the axle between said side wall portions and having portions of its free ends embedded in said transverse web.

35. 6. A wheeled toy which comprises a hollow molded body composed of flexible and elastic rubber-like material having spaced side wall portions provided at their bottoms with alined axle receiving notches, said body having an integral transverse web connecting said side wall portions of the body said transverse web lying in a plane containing the axes of opposing axle receiving notches and extending downwardly to the upper portions of said notches, an axle seated in said notches and having wheels mounted on the end portions thereof, and a sheet metal member having its central portion in engagement over the major extent of said axle between said side wall portions and having its end portions shaped for gripping engagement with said transverse web.

7. A wheeled toy which comprises a body member having depending spaced side wall portions and a transverse web portion disposed between said side wall portions, an axle disposed beneath said transverse web portion, said web and axle lying in a single transverse plane, wheels mounted on said axle, and a separate one-piece fastening member embracing opposed sides of said web portion and passing under said axle, said fastening member being securely connected to said body member to hold said axle to the underside of said web portion.
